WASHING MACHINE

Herbert L. Johnston and David A. Meeker, Troy,
Ohio, assignors to The Hobart Manufacturing
Company, Troy, Ohio, a corporation of Ohio

Application January 17, 1931, Serial No. 509,410

32 Claims.

(Cl. 141—9)

This invention relates to washing machines.

One of the principal objects of the invention is the provision of a washing machine which is simple in construction, is efficient in operation, is capable of handling large quantities of articles for rapid and thorough washing; and in which the passage of articles through the machine may be varied to provide a washing operation of regulated and controlled duration.

10 Another object of the invention is the provision of a washing machine in which the operation of the article feeding mechanism is automatically suspended during times that the passage of articles is obstructed, and is automatically resumed upon removal of the obstruction.

15 Another object of the invention is the provision in a washing machine of an article advancing mechanism incorporating an oscillating motion by which the articles are intermittently advanced through the machine, and which is readily reversible to provide a feeding movement in either of opposite directions; the mechanism comprising a frame suspension of flexible members freely movable, and capable of continued operation without deterioration or wear.

20 Another object of the invention is the provision in a washing machine of this character, having an intermittent advance of the articles to be washed during transit through the machine, of wash water jets which are positioned in coordination with the travel of articles through the machine to assure a uniform distribution of wash water and thorough cleansing of the articles.

25 A further object of the invention is the provision in a washing machine of rinsing jets which are actuated by the passage of articles to provide a thorough rinsing operation without waste of rinse water, and in which the rinsing operation is automatically terminated during periods of abnormal operation of the machine.

30 Other objects and advantages of the invention will be apparent from the following description, the accompanying drawings and the appended claims.

35 In the drawings, which illustrate a preferred embodiment of the invention—

40 Fig. 1 is a side elevational view of a washing machine constructed in accordance with this invention; some of the parts being broken away for clearness of illustration;

45 Fig. 2 is an end elevational view of the machine in which certain of the parts are broken away;

50 Fig. 3 is a horizontal section taken on the line 55 3—3 of Fig. 1;

Fig. 4 is a vertical section taken on the line 4—4 of Fig. 1;

Fig. 5 is a view of a portion of the feeding mechanism;

Fig. 6 is a view of a portion of the rinse water 5 control;

Fig. 7 is a view of a portion of the control for the feeding pawls;

Fig. 8 is a view of a portion of the feeding mechanism and pawl control; 10

Fig. 9 is a detail view of a part of a pawl rack of a carrier;

Fig. 10 is a view of a portion of the rinsing jet control;

Fig. 11 is a diagram illustrating the relationship between the spray spacing and the carrier movement; 15

Fig. 12 is a longitudinal vertical section through the machine illustrating a somewhat different form of carrier feeding mechanism; 20

Fig. 13 is a torque diagram of the overload release mechanism.

The drawings, in which like characters of reference designate like parts throughout the several views thereof, illustrate a washing machine which is adapted to receive articles to be washed, and is provided with feeding means to advance the articles through the operations of washing and rinsing; the articles being preferably placed in suitable carriers for transit through the machine. As shown, the washing machine comprises spaced uprights 10 which are joined by strengthening members 11 and a base 12 to provide a rigid rectangular structure. Mounted upon the structure is a housing 13 which contains the washing jets, and through which the carriers or articles to be washed are advanced by the feeding mechanism. The housing comprises a top wall 14, end walls 15 in which are provided suitable openings 16 for the entrance and removal of the carriers, side walls 17, and a bottom wall 18 which serves as a collector for the wash water, and which has formed to it a sump 19 into which the collector 18 drains. Suitable strainers 20 are placed at the entrance opening of the sump and serve to restrain the passage into the sump of solid waste material which has been washed from the articles passing through the machine. Mounted on the base 12 35

is a motor driven pumping and driving unit which actuates the feeding mechanism and provides the circulation of wash water. As shown, the shaft of the motor 22 is connected by a coupling 23 to the shaft 24 of a gear drive or speed 40

45

50

55

reducer 25 of conventional construction. The opposite end of the shaft 24 is connected by a coupling 26 to a centrifugal pump 27 having a suction connection 28 with the sump 19. The 5 pump discharge 30 is connected to branched conduits 31 and 32; the conduit 31 providing a supply of wash water to a lower jet structure 33 having upwardly directed nozzles, while the conduit 32 terminates in the supporting member 34 for 10 a rotary wash arm structure 35 having a plurality of jets 36 which are positioned to direct sprays of wash water downwardly onto the articles as they are passed through the machine.

For convenience in handling the articles that 15 are to be washed, suitable carriers 38 are provided into which the articles are placed for passage through the machine. As shown, a carrier 38 comprises a four-sided framework 39 of wood or other suitable material having a bottom 40 so 20 constructed that the sprays of wash water may readily pass therethrough. Trays which are to be used for carrying dishes and like objects through the machine may be constructed with spaced rods 41 which serve to position the articles 25 to permit thorough coverage by the washing jets. A carrier to support such articles may have a bottom 40 constructed of spaced parallel rods extending transversely to the members 41. Carriers which are to be used for the transportation 30 of silverware and such articles may be provided with a screen bottom 40 of such mesh that the articles may not pass through, but through which the jets of washing water may readily pass. The carriers are provided with handle grips 43 35 by which they may be readily lifted by the operator when placing them into position for passage through the machine, and the bottom edges of a pair of parallel side walls are provided with metal shoes 45 upon which the carrier moves 40 through the machine. When operating the machine the motor is usually permitted to run continuously during the entire period of use. The operator may insert the carriers within the machine as they become filled with articles to be 45 washed, or he may insert the carriers at intervals to permit a washing period of any desired duration.

For transit of the carriers through the machine a trackway is provided to support the carriers, 50 and means are provided for progressively advancing the carriers with respect to the trackway by a relative movement between the trackway and the carrier advancing means. This may be accomplished either by the use of a stationary 55 trackway with a movable advancing means, or through the use of a movable carrier supporting trackway with stationary advancing means so arranged as to retard movement of the carriers upon movement of the trackway in one direction. 60 As shown, the trackway comprises spaced members 48 of angular cross section which extend longitudinally through the machine from one end 15 to the other, and which are securely fastened by supporting brackets 49 from the framework 65 of the machine. The track members 48 stand with one leg of each angle extending vertically, and the other leg extending horizontally towards one another. The horizontally extending portions 70 serve to support the shoes 45 of the carriers as they pass through the machine, while the vertically extending portions act as guides. The ends of the track members are flared outwardly as shown at 50.

75 The carrier advancing means comprises a

framework which is suspended from the housing 13 and has an operating connection to the gear drive 25 for oscillating movement thereby. The rotating movement of the gear drive is translated by the drive connection into a back and forth movement of the carrier advancing frame which is of controlled amplitude and of periodic recurrence. Positioned on the frame are spaced members which are adapted to engage the carriers upon movement of the frame in one direction to thereby advance them relatively to the supporting trackways 48. As shown, the carrier advancing means comprises longitudinally extending rails 52 which stand parallel to the tracks 48, and which are attached by means of screws 53 to the arms 54 of end members 55 which extend transversely of the machine and, with the bars 52, provide a sturdy rectangular frame. The carrier advancing frame is supported within the machine by means of flexible straps 57 which are suspended from the housing 13 of the machine and are connected to the end members 55 of the frame. The straps 57 are preferably in the form of tapes of corrosion resisting metal, such as phosphor-bronze, which are suspended from 25 brackets 58 so that they may readily flex as the supported frame is oscillated by the driving mechanism. Such a suspension permits freedom of movement of the frame without having to resort to pivoted joints which are subject to wear and the necessity for replacement. While in the preferred embodiment shown in the drawings, the carrier advancing frame is suspended in the manner of a swing for oscillating movement about 30 finite radii, the frame can be mounted on rollers 35 or slides for reciprocating movement, or oscillation about infinite radii. Consequently, the expression "oscillating movement" as used herein refers not only to oscillation about finite radii but also oscillation or back and forth movement 40 about infinite radii, unless the contrary appears from the text.

The carrier advancing members comprise spaced pawls generally designated 60 which are pivotally mounted upon the rails 52 and are 45 spaced less than a carrier length apart so that as a carrier is advanced through the machine a second pawl will take up the advance of the carrier before the first pawl moves the carrier beyond its range of travel. As shown, each pawl 50 comprises an extending end portion 61 which is adapted to engage a carrier for advancement thereof, and an oppositely extending weighted end 62 which holds the engaging end portion in 55 engaging position by force of gravity. Each pawl 60 is supported from its bar 52 by means of a pivot stud 64. Rotary movement of a pawl 60 is limited by means of a pin 65 positioned on the bar 52 and extending between spaced overlying portions of the pawl. Each pawl 60 is provided with an elongated loop 66 which overlies the pin 65 and is positioned with respect to the pawl axis so that the pawl may swing within the 60 limits provided by the loop.

The carriers 38 are advanced by engagement of the pawls 60 with spaced lugs 70 which extend from the shoes 45. The lugs 70 are uniformly spaced and serve in effect as rack teeth with which the pawls engage in succession upon being oscillated with the carrier advancing frame. To 70 insure a uniform distribution of load between the pawls at the opposite sides of the machine the shoes 45 are all formed of like shape and are provided with upstanding end lugs 71 definitely spaced with respect to the lugs 70, and which 75

serve as guides for attaching the shoes to the rectangular frames 39 so that the lugs 70 will be positioned directly opposite to one another. The lugs 70 are spaced apart a distance equal to or 5 somewhat less than the oscillating travel of the carrier advancing frame, so that after having advanced the carriers upon feeding movement, the pawls will recede an amount sufficient to engage them behind the next succeeding lugs.

0 As mentioned, the pawls 60 are spaced apart a distance less than a carrier length and, as shown, three pairs of pawls are provided on the rails 52; one pair being provided adjacent each end of the machine while the remaining pair is positioned 5 adjacent the middle of the machine and within the range of the washing jets. As the carriers are advanced through the machine they are picked up in succession by each pair of pawls so that the carriers are moved intermittently at a steady 10 rate of advance. The speed of travel is such that all of the articles are subjected to the action of the washing jets for a sufficient length of time to thoroughly cleanse normally dirty dishes before they are carried from the range of the washing jets and into the range of the rinsing jets. To provide a rate of feed through the machine which would permit the carriers to remain within range of the washing jets for a length of time sufficient to thoroughly cleanse unusually dirty 15 dishes, such as those containing dried food which must be dissolved by an extended treatment under the washing jets, would needlessly limit the capacity of the machine for handling dishes which are easily washed. To permit regulation of 20 the duration of the washing operation a control is provided whereby the carriers are caused to dwell within the range of the washing jets when desired. The washing jets 33 and 35 are positioned midway through the machine, and the control 25 which regulates the passage of carriers is arranged so that the pawls 72 (Fig. 3) which advance the carriers through the washing station may be rendered inoperative for movement of a carrier. When these pawls are moved to 30 an inoperative position a carrier upon entering the machine is advanced by the first pair of pawls 73 until it is fed beyond the range of travel of this pair of pawls 73 and into the range of the washing jets. The carrier then remains stationary 35 until the control is actuated to render the washing station pawls again operative, or until the next following carrier advances through the machine a distance sufficient to push the preceding carrier forward until it is engaged by the last 40 pair of pawls 74 for movement from the machine.

The control which renders the pawls 72 inoperative is such that a dwell may be provided within range of the washing station, or the carriers may be progressively advanced through the machine as desired. To permit manual regulation of the passage of carriers a control arm 75 is positioned on the front of the machine within easy reach of the operator and is fixed to a shaft 76 which extends transversely of the machine; the 45 shaft being suitably supported from the framework to permit free rotational movement thereof. Spaced arms 77 are fixed to the shaft 76 and have attached to them extending plates 78 which lie directly beneath the paths of travel of the pawls 72 which are rendered inoperative upon actuation of this control. The plates 78 are attached to the arms 77 by means of screws 79 which extend through slots 80 in the plates to permit of a range of adjustment therefor. The plates 78 50 are provided with extending portions 82 which

are so shaped that upon movement of the control arm 75 to actuating position the plate portions 82 move pivotally to a horizontal position within and parallel to the path of travel of the pawls 72 to lift the ends 62 of the pawls so that the engaging ends 61 are forced downwardly to traverse a path out of engagement with the lugs 70 of the carriers. The horizontally extending portions 82 of the plates are greater in longitudinal extent than the oscillating movement of the pawls so that the pawls are supported in inoperative position throughout the extent of their movement. When the control arm 75 is moved to inoperative position the plates 78 move downwardly to a position out of engagement with the pawls so that the pawls may resume their normal position for advancement of the carrier.

The control is constantly urged toward a position which renders the pawls 72 inoperative by means of a coil spring 85 which encircles the rod 76. One end of the spring 85 is fixed to the rod 76 at 86 while the other end of the spring is secured to a stud 87 extending from the framework of the machine. The control handle is held in position to hold pawls 72 inoperative by the torsion of the spring 85 which holds a lug 91 on the control handle in engagement with the under side of a lug 90 extending outwardly from the machine frame. A second lug 89 is mounted on the machine frame in spaced relation to and beneath the lug 90, the control handle 75 normally being positioned between these two lugs. The control may be operated to release the pawls 72 and render them operative by the operator grasping the handle 75, which is normally held by the spring torsion up against the under side of lug 90, and pushing this handle down until lug 91 engages with the upper side of lug 89, this movement of the control handle serving to rotate shaft 76 and depress plates 78 below the range of pivotal movement of the pawls 72, so that these pawls are rendered operative to effect advancing feeding movement of the carriers out of the washing zone. As soon as the operator releases the handle 75, the spring 85 will return it to its upper position against the under side of lug 90, so that the particular pawls 72 associated with this control are then held in inoperative positions. The construction is also such that the control handle 75 may be locked in position to render the pawls 72 continuously operative to effect straight through feeding movement of the carriers. This is accomplished by pulling the handle 75 out axially against the compression of spring 85 a distance sufficient to enable the lug 91 to clear the relatively short lug 89, then turning it downwardly beyond lug 89 and releasing it to engage the lug 91 beneath the relatively short lug 89. Axial movement of the handle is resisted by the spring which tends to hold the lugs in engagement. The control is moved to operating position by pulling the control arm 75 outwardly an amount sufficient to permit the lug 91 to clear the lug 89 whereupon the control is rotated by the spring until the lug 91 engages the relatively long lug 90; the lug 90 being of sufficient length that the lug 91 may not pass it. The spring 85 bears at its outer end against a packing sleeve 93 of a gland 94 within which is provided suitable packing material to restrain leakage along the rod 76 to the exterior of the machine. The inclusion of this control permits the washing machine to be constructed with a relatively high speed rate of advance for the carriers which is coordinated with the capacity of the washing jets 75

to provide for thorough cleansing of easily washed dishes, and provides also a means whereby dishes that are difficult to wash may be permitted to remain within the washing station for as long a time as is necessary to clean them. The duration of the dwell is under complete control of the operator and may be terminated either by the introduction of another carrier of articles to be washed to move the preceding carrier within the range 10 of the pawls 74, or by actuation of the control to render the pawls 72 operative. Also, the use of this control permits the last carrier of articles sent through the machine during a period of use to be stopped at the washing station for as long 15 as desired and then be moved out of the machine without the necessity of sending an empty carrier through to advance the preceding carrier to within range of the last pawl 74.

Oscillating movement of the carrier advancing 20 frame is provided through a drive mechanism which connects the frame with a rotating crank arm 100 of the gear drive 25. A pivotal connection is provided between the arm 100 and a link 101; the connection incorporating an adjustment 25 whereby the effective length of the link 101 may be varied so as to vary the relative setting or positioning of the parts of the drive for the oscillating carrier advancing frame. The link 101 is pivotally connected at 104 to one end of a lever 30 105 which is pivotally mounted at 106 upon brackets 107 suitably supported upon the member 11 of the machine frame. As shown, the pivotal mounting 106 comprises stub shafts 108 which are held to opposite sides of the lever 105 and extend 35 oppositely therefrom in axial alignment for reception within the brackets 107. The opposite end of the lever 105 has a link 110 pivotally connected thereto at 111 which in turn is pivotally connected at 112 to a cross member 55 of the 40 carrier advancing frame. As the crank 100 of the drive 25 rotates, the frame is caused to oscillate to provide for progressive advance of the carriers through the machine.

The driving mechanism incorporates an over- 45 load release whereby the feeding movement may be suspended upon encountering resistance in excess of a predetermined amount such, for example, as may be encountered upon a carrier striking an obstruction which prevents its further 50 advance. This overload release in the driving means is accomplished by constructing the lever 105 in two parts and by resiliently connecting these parts so that the driving force is transmitted to the carrier advancing frame only when 55 the tension holding the two parts of the lever together exceeds the driven load. As shown, that portion of the lever 105 to which the link 110 is attached comprises a bell like housing 114 from which the stub shafts 108 project. Spaced rods 60 115 which lie parallel to the support axis 106 extend across the open mouth of the member 114 and provide a support for the opposite end 117 of the lever to which the link 101 is pivotally connected. The member 117, like the member 114 is 65 of bell like form and of such size as to be received within the open end of the member 114. At the point of engagement with the rods 115 the member 117 is provided with V-shaped slots 118 which provide spaced pivot axes about which the member 70 117 can move with respect to the member 114. This pivotal movement is restrained by the provision of springs 120 which extend between a rod 121 carried in the member 114 and a bracket 122 which is adjustably carried by a screw 123 located 75 in the member 117. Upon assembling the two

parts 114 and 117 of the lever the springs 120 are tensioned by turning the screw 123 so that the two parts of the lever are held together as one under tension of the springs 120. By being so tensioned the lever 105 will transmit movement as a one piece lever until the load transmitted exceeds the torque produced by the tension of the springs 120 whereupon a further increase in load will cause the lever parts 114 and 117 to move relatively to one another by pivotal movement upon one of the rods 115. The spring bracket 122 is arranged so that the tension of the two springs 120 is equalized. As shown, the bracket 122 comprises a circular bar 125 which extends transversely of the bracket and is threaded to receive the screw 123. The bar 125 serves as a pivotal mounting for the yoke portion 126 of the bracket so that the yoke 126 may shift to permit a uniform pull by the springs. Variation in tension is secured by rotation of the screw 123.

As illustrated more particularly in Fig. 13, the overload release is constructed so that the driving torque applied through the pivotally connected parts 114 and 117 is of a controlled value when the parts are coupled together in their normal operating relationship, as shown in position 1, and also in Fig. 5, and so that this driving torque does not increase to an objectionably high value such as to impose undue strain upon the parts when the overload release functions and the pivotally connected parts 114 and 117 move relatively to each other to their open or broken position. In the coupled position of position 1 of Fig. 13, the maximum driving torque is represented by the product of the spring tension f' , which is a direct function of the length l' and the effective moment arm a' . When an abnormal resistance to feeding movement is encountered in the machine which exceeds this torque, then the pivotally connected parts 114 and 117 break, the part 117 moving about one or the other of the pins 115, depending upon the direction of travel of the arm 101 and part 117 at the time of release. Assuming that the arm 101 and part 117 are traveling toward the right (as shown in Fig. 13) at the time of release, then the part 117 will move about the right hand pin 115 as a pivot to the position indicated in the drawing as position 2. Inasmuch as the driving connection may release at the time the arm 101 and part 117 are completely at one end or the other of their strokes, provision is made for pivotal movement of the part 117 relative to the part 114 for the complete amplitude of travel of the arm 101, and corresponding amplitude of pivotal movement of the part 117 about either of the pins 115, which in actual practice may involve an angular movement of the part 117 about a pin 115 of 30° or more. As the part 117 pivots about the pin 115, while the part 114 remains stationary due to jamming of the racks or other abnormal operating condition, the length of the spring gradually increases until the limiting position 2 is attained, so that the spring tension f^2 is somewhat increased. However, due to the relative arrangement of the parts including the positioning of the cross pin 121 above and intermediate the pins 115, the length of the moment arm represented by the line drawn from the pivot pin 115 normal to the center line of the spring 120 progressively decreases at a rate arranged to counteract to a predetermined extent, or even to more than counteract, the length increase and increasing spring tension, until in position 2 it has decreased to the short moment arm indicated at a^2 . The parts

are so proportioned and arranged that the product of f^2 and a^2 is not materially greater, and is preferably less, than the product of f' and a' ; consequently the actual driving torque exerted by the springs 120 between the parts 117 and 114 in their extreme open or broken position as indicated in position 2 has not materially increased but may have even decreased from that which is exerted in the normal operating position of position 1. The net result is that substantially the maximum driving torque is exerted when the parts are closed and the machine is functioning normally; the torque can be regulated and predetermined to provide a desired releasing force which must be attained or exceeded to produce breaking of the parts, such as upon jamming of the racks; the overload release can release in either direction of oscillating movement and in any position of its range of movement; and after the parts of the 15 overload release have broken upon encountering a resistance to movement greater than the driving torque f' , a' normally holding the parts together, the effective driving torque then does not materially increase but in fact may decrease as 20 the parts approach maximum broken position represented by the torque f^2 , a^2 . The driving strain exerted by the part 114, lever 110, oscillating frame 52 and pivoted dogs 60 upon the jammed racks is thereby maintained at a desired low force value 25 which is regulated to prevent injury thereto; and during a part of the relative pivotal movement of the parts 114 and 117 on each cycle of oscillating movement the driving strain may be even reduced below this value. As soon as the jamming of the racks or other obstruction causing the resistance to feeding movement is overcome, the parts 114 and 117 automatically resume their 30 normal operating position shown in Fig. 5, and normal feeding movement is automatically resumed.

In some instances the washing machine is so installed that the carrier table 128 extending from the outlet end 130 of the machine (see Fig. 10) terminates a short distance from the machine due, for example, to the installation being such that an end wall of the room prevents further extension of the table 128, or because it is desirable to have the table continue at a right angle as shown at 131. Such an arrangement limits the 40 travel of the carriers 38 beyond the outlet end of the machine and, if they are not removed by the operator, they may fill up solidly the space from the end wall 132 of the table in through the washing machine so that further advance of the carriers is prevented. When such conditions 45 arise, or if an article should so project from a carrier as to cause an obstruction to the feeding movement, the advance of the carriers stops upon encountering such resistance and provision of the overload release in the form of the resiliently held two part lever permits the driving movement of the drive gear 25 to continue even though feeding motion is restrained. Upon removing the 50 trays of washed articles, or removing the obstruction which has caused a cessation of feeding movement, the feeding motion is again resumed just as soon as the driven load becomes less than the tension holding the parts of the lever together. This stoppage of feeding motion and resuming of movement occurs automatically and 55 without any attention from the operator of the machine.

Rinsing jets 135 are positioned toward the outlet end of the machine from the washing station 75 so that the carriers upon being advanced beyond

the washing station are subjected to sprays of rinsing water before passing from the machine. As shown, the rinsing jets 135 are positioned both above and below the path of travel of the carriers so as to direct sprays from both directions toward the carriers. The jets 135 are spaced upon a pipe structure having a horizontally extending portion 137 extending transversely of the machine beneath the path of travel of the carriers and connected to an upright pipe 138 from which a second horizontally extending jet carrying pipe 139 extends parallel to the pipe 137 and above the path of travel of the carriers. The pipe 138 terminates in a union connection 140 for attachment to a rinse water conduit 141 extending lengthwise of the machine and terminating at its opposite end in a closed pipe end having a union connection 140' symmetrically positioned longitudinally of the machine with respect to the union 140. A supply pipe 142 which connects to the conduit 141 10 is provided with a normally closed valve 143 having a control which is adapted to be actuated upon passage of a carrier to open the valve and supply rinse water to the jets only during the time that a carrier is within range of the jets. The 15 control for the rinse valve 143 comprises an arm 145 which is pivotally supported upon a shaft 146 extending from a bracket 147 of the machine frame. The arm 145 terminates in a finger 148 which stands normally within the path of travel 20 of the carriers so that upon entrance of a carrier within the range of the rinsing jets the arm 145 will be moved pivotally to open the rinse valve. The hub portion 150 of the control arm is provided with oppositely positioned spaced lugs 151 25 and 151'. As shown, the lug 151 has pivotally connected to it a link 153 which terminates in a universal joint connection 154 which is attached to the operating lever 155 of the valve 143. The 30 valve 143 is preferably of a conventional form in which the valve stem is depressed to provide a passage through the valve. A spring is incorporated in the valve structure to constantly urge the valve to closed position and this spring serves also to urge the connected control arm toward a 35 position in which the finger 148 stands within the path of the carriers. Such movement of the control arm is limited by a pin 157 which extends through the arm 145 and is adapted to contact with the upstanding leg of one of the track members 40 45 50 55 60 65 70 75 80 85 machine and fill up the entire space on the table 128 to the end wall 132 so that further advance of the carriers is prevented, the arm 163 upon being encountered by the advancing carrier is 5 caused to swing against the tension of the spring 164 to permit the valve 257 to close so that the supply of rinse water is shut off to thereby prevent waste of rinse water through the jets until the advancing movement of the carriers is again 10 resumed by removing the trays of washed articles to so release the lever 159. Such an arrangement of parts permits each carrier of articles to be thoroughly rinsed by permitting the rinse water to flow during the time that the carrier is 15 advanced, but an excess flow of rinse water is prevented by shutting off the supply whenever the advancing movement is stopped.

The machine is readily adaptable to a variety 20 of installation conditions by being convertible for operation in either direction upon a simple rearrangement of few parts of the machine. As shown in Fig. 1, the machine is arranged to advance carriers from right to left. Should it be desirable to reverse the direction of travel this 25 may be readily accomplished by removing the pawl carrying bars 52 of the carrier advancing frame and turning them end for end so that the bar mounted toward the rear when the machine is feeding in a left hand direction will be attached 30 to the front of the machine for feeding movement in a right hand direction. This reversal of parts is accomplished by removing the screws 53 which hold the bars 52 to the end portions 55 of the frame, and by replacing the screws 35 upon reversing the bars. The remainder of the feeding mechanism remains unchanged for feeding movement in either direction and, by being symmetrically arranged, the overload release of the lever 105 operates equally well when feeding 40 in either direction. Reversal of feeding movement necessitates no change in the control by which the washing station pawls are rendered ineffective to feed the carriers as this control is positioned centrally of the length of the machine 45 and operates to engage the pawls when feeding in either direction.

When reversing the direction of operation of the machine it is necessary to change the rinsing jets so that they will be positioned at the 50 outlet end of the machine. To change the position of the rinsing station it is only necessary to detach the jets and their supporting piping at the union 140, and attach this piping to the union 140' at the opposite end of the machine. 55 The rinse control valve 143 remains unchanged while its control arm 145 is turned end for end on its hub 150 so that it will extend in the direction of the rinsing jets. Reversal of the control arm hub brings the lug 151' to a position 60 where the link 153 may be connected to it, and as this lug extends oppositely from the lug 151 the valve will be opened upon engagement of the control arm fingers by a carrier. The limit pin 157 by extending in opposite directions from the 65 arm 145 serves in either position of assembly. Both end portions of the hub 150 are threaded as indicated at 170 and a cap member 171 is provided to enclose the exposed hub end against entrance of moisture. The member 171 serves 70 as a housing for the nut 172 by which the control arm is held to the shaft 146, and also provides for attachment of a grease cup 173 by which lubricant may be introduced to the control arm hub.

75 Splashing of water from the machine as well as

contamination of the rinsing operation by entrance of washing water is prevented by the use of fabric curtains 175 which are suspended from the machine housing. The curtains 175 are preferably made of duck or some other suitable material and are each provided with a cross rod 176 of sufficient length to extend beyond the curtain width as shown at 177 to permit suspension of the curtains from hook members carried by the housing of the machine. As shown, a curtain is 10 suspended adjacent the entrance opening of the machine from hooks 178. Additional hooks 179 provide support for a curtain which hangs between the washing station and the rinsing station, while another set of hooks 180 suspend a 15 curtain beyond the rinsing station to prevent splashing of rinse water from the machine. Additional hooks are provided and are positioned within the machine symmetrically to those described so that when the feeding movement is in a right hand direction the curtains may be suspended accordingly. Under such circumstances the curtain shown suspended from the hooks 179 would be suspended from the symmetrically positioned hooks 179', while the curtain suspended 25 from the hooks 180 would be transferred to the hooks 180'. The curtain hanging at the entrance end from the hooks 178 would also be transferred to the opposite end of the machine.

The upper washing jets 36 are positioned upon 30 a wash arm structure 35 which is adapted to be rotated by the reaction forces of water issued from the jets. The arm 35 is suspended from a bearing mounted in the housing 34 and the arrangement of parts is generally similar to that disclosed in the copending application of Herbert L. Johnston, Serial No. 478,978, filed August 30, 1930.

The lower jet structure 33 comprises a stationary header casting 186 which is connected to the 40 conduit 31 and is provided with spaced pairs of axially aligned oppositely opening outlets 187 to which the nozzle arms 188 are removably attached. The nozzle arms 188 are each provided with spaced jets 36, and an extending sleeve 45 portion 189 which extends within the header 186 where it is adjustably held by means of a thumb screw 190. The interfitting relationship of the sleeves 189 within the header 186 is such that the individual nozzle arms 188 may be independently 50 adjusted as desired. Also, such an arrangement permits the nozzle arms 188 to be readily removed for access to the strainers 20 so that the strainers may be easily taken from the machine for 55 cleaning.

The jets 36 of the lower jet structure are positioned to provide a uniform distribution of wash water within the extent of the washing station, and the sprays are directed so that each time a carrier comes to rest within the washing station 60 a different spray pattern is played upon the articles. The relationship between the jets and the extent of a carrier movement is preferably such that the spacing between adjacent jets is somewhat different than the carrier movement so that each time the carrier comes to rest the sprays will be directed toward different regions of the carrier. Adjacent jets preferably stand angularly related to one another, as shown in Fig. 11, so that each time a carrier comes to rest a given 70 general region of a carrier will be acted upon by sprays directed toward the carrier at different angles from the sprays at the preceding position of rest. An arrangement of sprays as described permits effective washing of articles such as 75

5 cups, bowls, and such hollow articles which are preferably positioned in the carriers in an inverted position so that the interiors thereof are exposed for cleaning by sprays from the lower jet structure. By providing a spacing of jets different than the amount of a carrier movement, and by directing these jets at different angles, a uniform distribution of wash water is supplied whereby the sprays act effectively on all parts 10 of a carrier. The normal intervals of rest together with the spacing of and the angular relationship of the sprays permits each region of a carrier to be subjected to a spraying action of sufficient duration to clean articles which are 15 easily washed, while articles more difficult to clean, by provision of a control permitting a dwell at the washing station, may be subjected to washing action of any duration beyond that provided in the normal passage of articles 20 through the washing zone.

25 A pipe fitting 192 is provided between the pump outlet 30 and the conduits 31 and 32 to the washing nozzles. The pipe fitting 192 is provided with passages to the several conduits which are so regulated as to size as to create a balanced flow of water to the nozzles, the flow regulation being such that the force of water from the upper nozzles plus the weight of the articles being washed is sufficient to prevent the force of water 30 from the lower nozzles from displacing the articles.

35 As mentioned, the carriers may be advanced through the machine by provision of an oscillating carrier support and stationary advancing means positioned to move the carriers relatively to the support upon movement of the carrier support in one direction. Such an arrangement of parts is illustrated in Fig. 12 which shows a horizontally disposed carrier frame 200 comprising parallel extending side rails or tracks 201 and interconnecting end members 202 suspended for oscillating movement within the washing machine housing. The suspension is generally similar to that shown in Fig. 1 for an oscillating 40 feeding frame, and comprises metal tapes 203 which are attached to each corner of the frame 200 and are suitably supported from brackets 205 on the machine housing. The free flexing of the tapes 203 permits the frame 200 to be oscillated 45 by rocking movement of a driving lever 206 having a link connection 207 with an end member of the frame 200. The lever 206 is rocked as by means of the gear drive shown in Fig. 1 which may be operatively connected to the lever as by 50 means of the link 208.

55 The carriers are placed upon the track frame 200 by being inserted through the open end 210 of the housing, and are advanced through the machine by engagement with pawls 212 which are 60 pivotally mounted from the machine housing in position to engage the spaced lugs 70 of the carriers. The pawls 212 are free to rock on their axes 213 which are held in fixed relation to the housing and serve to restrain movement of the 65 carriers with the frame 200 as the frame swing in the direction against which the pawls hold. The carriers move with the frame by frictional contact therewith as the frame swings to the left, and are held by the pawls 212 so as to be 70 moved relatively to the frame as it swings to the right. The pawls 212 are so spaced throughout the longitudinal extent of the machine that upon oscillation of the frame 200 the carriers are moved through the machine in a succession of intermittent 75 movements at a steady rate of advance. As

shown, the pair of pawls designated 217 are positioned adjacent the entering end of the machine and are spaced less than a carrier length from the pawls 218 which are positioned adjacent the middle portion of the machine and within the range of the washing jets; some of which are shown diagrammatically at 220. A third pair of pawls numbered 221 are positioned adjacent the outlet end of the machine and, as shown, are spaced from the pawls 218 a distance equal to or less than a carrier length plus the amount of one carrier movement. As the carrier is advanced through the machine it moves progressively past the pawls 217 then past the pawls 218 until these latter finally engage the rear face of the carrier frame. The following right-hand movement of the frame 200 causes the carrier to be held against the pawls so as to be advanced relatively to the frame and upon the next left-hand movement of the frame the carrier is brought within operating 20 range of the pawls 221.

With such a feeding arrangement the carriers move forwardly on the left-hand swing with the frame due to frictional contact therewith, and are held against pawls 212 on the right-hand swing for advance relative to the supporting frame. This advance of carriers may continue until further advance is obstructed as by the occurrence of a condition such as is illustrated in Fig. 10 wherein the carriers are prevented from further advance by an obstruction in the path of the first carrier. When a condition arises which prevents further feeding, the carriers, by being frictionally held to the frame only by their own weight, are caused to slide relatively to the frame upon left-hand feeding movement of the frame. During right-hand movement those carriers still supported by the frame will tend to move with the frame until further movement is prevented by engagement with pawls 212. When 40 an obstruction, which prevents further advance of the carriers, occurs at a point other than at the extremes of an advancing movement the carriers on the frame are caused to oscillate with the frame through whatever space exists between 45 the obstruction encountered upon left-hand movement and the pawls encountered upon right-hand movement and consequently those carriers within range of the washing jets are subjected to the action of relatively moving sprays. 50

55 A control 223 is provided whereby the pawls 218 may be rendered inoperative when desired so as to provide a dwell for the carriers at the washing station. This control is generally similar to that operated by the arm 76 and, like that control, may be operated manually to provide for either continuous advance of the carriers through the machine or a dwell at the washing station. With the pawls 218 held in inoperative position by the control 223 a carrier upon being entered 60 within the machine is advanced by the pawls 217 until it passes beyond operating range of these pawls. As, with the pawls 218 inoperative, there is no means for providing further advance of the carrier, it is caused to oscillate with the frame 65 200, and to continue such movement either until the pawls 218 are released or until the next succeeding carrier advances the carrier at the dwell position an amount sufficient to be engaged by the pawls 221. A carrier while in the dwell position 70 75 is rocked slowly back and forth with the frame within the range of the washing jets so that a thorough washing operation results. It is thus seen that the carriers or racks of articles to be washed are moved back and forth in a certain 75

washing or treating zone of the machine during the dwell in this form of the device. For purposes of description, the term "dwell" is used herein to connote either the stationary positioning of a carrier within a certain zone of the washing machine during a cessation of advancing feeding movement, or a local movement of the carrier within such a zone without advancing feeding movement, whereby superior washing and cleaning action is obtained. The back and forth local movement of a carrier without advancing feeding movement may be characterized for purposes of description as an "oscillating dwell". With an arrangement such as that described in which the carriers are held to the frame only by frictional engagement, the driving lever 206 need be only a solid one piece member as upon obstruction to carrier advance the carriers are free to slide relatively to the frame.

Should it be desirable to provide positive means to move the carriers with the frame 200 instead of relying upon frictional engagement this can be readily accomplished by attaching pawls to the frame as shown at 225. These pawls 225 are pivotally attached to the carrier tracks 201 and prevent movement of the carriers relatively to the frame in the direction of travel of the frame in which the carriers move relatively to the fixed pawls 212. The pawls 225 are pivotally connected at 226 to the tracks 201 in spaced relation to the pawls 212. Suitable means are provided on the pawls 225 to limit their rocking movement and as shown, comprise spaced lugs 227 which stand from the pawls in positions to engage the horizontal legs of the angularly formed track. The pawls 225 are formed with weighted end portions 228 which tend to hold the pawls in position so that the carrier engaging end 229 of the pawls will stand in the path of travel of the carriers.

The provision of the pawls 225 permits positive advance of the carriers through the machine and prevents failure of the feeding motion due to slippage of the carriers on the frame, or to the carriers encountering a slight obstruction just sufficient to overcome the frictional engagement of the carriers such for example as when a carrier advances to the point where it engages the control arm 145 for the rinse valve. Under certain conditions the control arm may require more force to open it than is available through frictional contact of the carriers with the track and the pawls 225, by providing positive movement, insure proper advance of a carrier. The pawls 225, as mentioned, are provided in spaced relation to the pawls 212; one pair 232 being positioned adjacent the entering end of the machine while a second pair 233 stands relative to the pawls 218, and a third pair 234 are positioned adjacent the last pair of stationary pawls 221.

The movable pawls 233 provide for positive passage of a carrier past the position of engagement with the rinse water control arm, while the pawls 234 are positioned to positively advance the carrier beyond the range of this control arm so that it is not possible for a carrier to stand in such position that the rinse valve is held in open position as might occur when depending only upon frictional contact for carrier advance.

When the feeding movement for the carriers is provided by an oscillating supporting frame having pawls 225 for positively holding the carriers against backward movement relative to the frame 200 an overload release is incorporated in the driving lever 206 similar to that illustrated in Fig. 5 so that when an obstruction to carrier advance

is encountered the driving means may move independently of the feeding means.

The several different forms of feeding mechanism described possess in common the feature that a dwell may be provided in the carrier advance whereby a carrier may be subjected to the washing action for so long a period as desired, and is at all times under control of the operator.

While the forms of apparatus herein described constitute preferred embodiments of the invention, it is to be understood that the invention is not limited to these precise forms of apparatus, and that changes may be made therein without departing from the scope of the invention which is defined in the appended claims.

What is claimed is:

1. In a washing machine adapted to receive carriers of articles to be washed during transit through the machine; means for supporting the carriers during transit, means for advancing the carriers relatively to the supporting means, one of said means including a suspension frame, means supporting said frame for oscillatory movement comprising straps attached at one end to the frame and at the other end to a stationary part of the machine, means for imparting an oscillatory movement to said suspension frame, said carrier advancing means comprising members adapted to engage the carriers during movement of the oscillatory suspension frame in one direction for advance of the carriers relative to the supporting means.

2. In a washing machine adapted to receive carriers of articles to be washed during transit through the machine; means for supporting the carriers during transit, means for advancing the carriers relatively to the supporting means, means for imparting an oscillatory movement to one of said means, said carrier advancing means comprising members spaced longitudinally of the machine adapted to engage the carriers during movement of the oscillatory means in one direction for advance of the carriers relative to the supporting means, and means for rendering at least a part of said members ineffective to advance the carriers relative to the supporting means.

3. In a washing machine having a washing zone located centrally of the machine and adapted to receive carriers of articles to be washed in said washing zone during transit through the machine; means for supporting the carriers during transit, means for advancing the carriers relatively to the supporting means comprising a frame adapted to oscillate parallel to carrier travel, driving means connected to the frame for imparting an oscillatory movement thereto, side rails for the frame, means for reversibly receiving the side rails on said frame for reverse operation of the machine, spaced pawls on the side rails adapted to engage and advance carriers in one direction, said pawls being positioned on the side rails so that in either position of use of the rails the pawls are effective to advance the carriers on both sides of the washing zone and are ineffective to advance the carriers at the washing zone.

4. In a washing machine adapted to receive carriers of articles to be washed during transit through the machine; means for supporting the carriers during transit, means for advancing the carriers relatively to the supporting means, means for imparting an oscillatory movement to one of said means, said carrier advancing means comprising spaced pawls mounted to engage the carriers during movement of the oscillatory means

in one direction for advance of the carriers relatively to the supporting means, means for reversibly mounting said pawls for advancing the carriers relatively to the supporting means in either direction through the machine, and means for rendering at least a part of said pawls ineffective to advance the carriers relative to the supporting means, said last named means being operative in either of the reversible mountings of 10 said pawls.

5. In a washing machine comprising washing apparatus arranged to provide a washing station and adapted to receive carriers of articles to be washed during transit through the machine; 15 means for supporting the carriers during transit, means for advancing the carriers relatively to the supporting means, means for imparting an oscillatory movement to one of said means, said carrier advancing means comprising pawls spaced longitudinally of the machine and mounted to engage the carriers during movement of the oscillatory means in one direction for advance of the carriers relative to the supporting means, and means for moving the pawls within the range of the washing 20 station to a position ineffective to advance the carriers relative to the supporting means to thereby provide a dwell of the carriers in desired washing position.

6. In a washing machine adapted to receive carriers of articles to be washed during transit through the machine; means for supporting the carriers during transit, means for moving the carriers through the machine including dogs engaging the carriers and moving them relative to 30 the said supporting means, means for rendering a part only of said dogs inoperative for interrupting the movement of a carrier through the machine to provide a dwell of the carrier at a predetermined position within the machine, said 35 moving means including dogs remaining operative to move a succeeding carrier into contact with the previous carrier to push the previous carrier out of the dwell position, and means for rendering the inoperative dogs operative so that the moving 40 means then operates to move the carriers straight through the machine without said dwell.

7. In a washing machine having a washing station, an oscillatory frame for supporting articles to be washed within the machine, means 50 for imparting an oscillatory movement to said frame, means cooperating with said oscillatory frame for advancing articles along said frame during oscillatory movement thereof, said advancing means being effective on both sides of 55 the washing station and ineffective at the washing station whereby the advancing movement of the articles is stopped at the washing station so that the articles have an oscillating dwell at the washing station.

8. In a washing machine having a washing station, an oscillatory frame for supporting racks of articles to be washed within the machine, means for imparting an oscillatory movement to said frame, means cooperating with said oscillatory 60 frame and arranged adjacent the inlet end of the machine for advancing racks of articles along said frame as far as the washing station during oscillatory movement of said frame, and additional advancing means cooperating with said oscillatory frame and arranged adjacent the outlet end of said machine for advancing racks of articles along said frame toward the outlet of the machine during oscillatory movement of said frame, 70 said advancing means adjacent the inlet end 75

of the machine being operatively spaced from the advancing means adjacent the outlet end of the machine to terminate advancing movement of a rack of articles at the washing station, whereby the rack oscillates back and forth with 5 the frame at the washing station until a succeeding rack is fed by said advancing means adjacent the inlet end into the washing station and pushes the preceding rack out of the washing station, said additional advancing means adjacent the outlet end then picking up the said preceding rack after it has been pushed out of the dwell position and moving it along the oscillatory frame toward the outlet end of the machine.

9. In a washing machine comprising washing 15 apparatus arranged to provide a washing station and adapted to receive carriers of articles to be washed during transit through the machine; means for supporting the carriers during transit, means for advancing the carriers relatively to the supporting means, means for imparting an oscillatory movement to one of said means, said carrier advancing means comprising pawls spaced longitudinally of the machine and mounted to engage the carriers during movement of the oscillatory means in one direction for advance of the carriers relatively to the supporting means, means for moving the pawls within the range of the washing station to a position ineffective to advance the carriers relative to the supporting means, and control means for said moving means providing for continued advance of the carriers or a dwell at the washing station as desired. 30

10. In a washing machine adapted to receive carriers of articles to be washed during transit 35 through the machine; a suspension frame for supporting the carriers during transit, flexible straps fixedly connected adjacent their upper ends to a stationary part of the machine and adjacent their lower ends to said suspension frame 40 to freely suspend said frame, means for imparting an oscillatory movement to said suspension frame, means for advancing the carriers relatively to the suspension frame, said carrier advancing means comprising members adapted to 45 engage the carriers during movement of the suspension frame in one direction for advance of the carriers relatively to the suspension frame.

11. In a washing machine adapted to receive carriers of articles to be washed during transit 50 through the machine; means for supporting the carriers during transit, means for imparting an oscillatory movement to said supporting means, means for advancing the carriers relatively to the supporting means, said carrier advancing means comprising members adapted to engage the carriers during movement of the supporting means in one direction for advance of the carriers relatively to the supporting means, and means for moving at least a part of said members 55 to a position ineffective to advance the carriers relatively to the supporting means, whereby the carriers adjacent said part of the members can oscillate with the supporting means. 60

12. In a washing machine, means for supporting carriers of articles to be washed, means for advancing the carriers of articles through the machine, said carrier advancing means comprising a horizontally disposed frame, supporting means for said frame including suspended flexible straps attached thereto, means for imparting an oscillatory movement to said frame, and members carried by said frame and adapted to engage and move the carriers relative to the 70 75

said supporting means during oscillatory movement of said frame in one direction.

13. In a washing machine, means for supporting carriers, of articles to be washed during transit through the machine, oscillating feeding means for advancing the carriers in repeated steps relative to the supporting means, driving means for the feeding means providing a feeding stroke for engagement with and advance of the carriers and a return stroke, said feeding means being reversibly attachable for feeding operation in either of opposite directions, yielding motion transmitting means operable in either direction of machine operation comprising interconnected members of which one connects to the feeding means and the other connects to the driving means for movement therewith, resilient means holding said members under a maintained tension and acting under normal load conditions to hold the members in predetermined relationship, said resilient means being adapted to yield in either direction of movement of said motion transmitting means upon subjection to an excessive carrier advancing load for relative movement of the members during existence of the excessive load and to return the members to normal relationship upon termination of the excessive load so that the normal relationship exists except under excessive load conditions and normal reciprocating operation is maintained for ready withdrawal of carriers during the return stroke of normal operation.

14. In a washing machine comprising washing apparatus arranged to provide a washing station, a movable supporting means for carriers of articles to be washed during transit through the machine, driving means imparting an oscillatory movement to said supporting means, feeding means for intermittently advancing the carriers with respect to the supporting means, and means to render said feeding means ineffective for further intermittent advance of a carrier within the range of the washing station during continued movement of the supporting means for effecting local movement of the said carrier within the range of the washing station without advance of the carrier out of said range.

15. In a washing machine, means for supporting racks of articles to be washed, means for advancing said racks through the machine, one of said means including an oscillatory frame, said advancing means including dogs spaced longitudinally for engaging the racks to advance the racks relative to their supporting means in stepped amounts during oscillation of said frame in one direction, means for imparting an oscillatory movement to said frame including a driving mechanism and interconnections between said driving mechanism and said frame, said interconnections including an overload release comprising a lever pivotally mounted adjacent the central portion thereof and having two end parts extending oppositely from the central portion and yieldingly connected in normally fixed relation to each other under predetermined tension to transmit a driving force from said driving mechanism to said frame to oscillate the same, said two parts moving relative to each other while maintaining the said yielding connection when said frame encounters a predetermined resistance to movement to thereby terminate rack advancing movement of said frame at any position within the range of oscillation thereof and while maintaining continued operation of said driving mechanism, said yielding connection between the two

parts of said overload release then providing for continued oscillation of said frame throughout that portion of its normal range of oscillation behind the point where the said predetermined resistance is encountered to thereby intermittently relieve the racks from the application of forward feeding force during the continued operation of said driving mechanism thus providing for ready removal of the racks during such intervals of relief.

16. In a washing machine, means for supporting carriers of articles to be washed during transit through the machine oscillating feeding means for advancing the carriers in repeated steps relative to the supporting means, driving means for the feeding means providing a feeding stroke for engagement with and advance of the carriers and a return stroke, yielding motion transmitting means comprising interconnected members of which one connects to the feeding means and the other connects to the driving means for movement therewith, resilient means holding said members one against the other in abutting relationship under a maintained tension and acting under normal load conditions to hold the members in predetermined relationship one in extension of the other, said resilient means being adapted to yield upon subjection to an excessive carrier load whereby one member rocks on the other member as a fulcrum for relative movement of the members during existence of the excessive load and to return the members to normal relationship upon termination of the excessive load so that the normal relationship exists except under excessive load conditions and normal reciprocating operation is maintained for ready withdrawal of the carriers during the return stroke of normal operation.

17. In a washing machine having a casing, means in said casing for supporting carriers of articles to be washed, and means for moving carriers through the casing in succession; a spray jet supported within the casing to direct a spray of liquid on the carriers of articles as they are moved through the casing, a supply pipe for said spray jet, a normally closed valve in said supply pipe, a carrier operated control for said valve positioned to open said valve for operation of the spray when a carrier is within range of the spray, a receiving space for racks beyond the discharge end of the casing and in alignment therewith to receive racks as they are moved out of the casing, a normally open valve in said supply pipe, and carrier operated control means for said last named valve positioned in said receiving space in the path of movement of the carriers for actuation thereby to automatically shut off the supply of liquid to the spray jet by closure of the normally open valve for so long as the control is actuated by the presence of a carrier at the control position.

18. In a washing machine having a casing and having means for moving carriers of articles to be washed through the machine casing; spraying mechanism for directing sprays of liquid upon the carriers throughout a predetermined range of movement as such carriers pass through the machine, means for automatically supplying liquid to the spraying mechanism as a carrier normally moves through the said range, a carrier receiving space extending from the discharge end of the casing and in alignment therewith, said carrier receiving space having a terminal obstruction, and means automatically operable for terminating the supply of liquid to said spraying mech-

anism by engagement of a carrier with the terminal obstruction.

19. In a washing machine having a casing, means in said casing for supporting and guiding racks of articles to be washed, means for moving the racks through the casing, a spray jet for directing a liquid spray upon the racks as they are passed through the casing, means controlling the supply of liquid to said spray jet, a member positioned in the path of movement of the racks in said casing for engagement thereby for automatically actuating said controlling means to supply liquid to the spray jet, a receiving space for racks beyond the discharge end of the casing and in alignment therewith to receive racks as they are moved out of the casing, and a second member positioned in said receiving space in the path of movement of the racks for engagement thereby after they are discharged from the casing for automatically terminating the supply of liquid to said spray jet.

20. In a washing machine having means for moving carriers of articles to be washed and adapted to convey the carriers in either of opposite directions through the machine; supply piping arranged to convey rinse water to a rinsing position, said piping terminating in outlets arranged to receive a rinsing jet adjacent either of opposite ends of the machine, a supply valve 30 permanently attached to said piping, and control means for said valve mounted in the path of travel of the carriers, said control means being reversibly attachable for operation of the valve upon contact with a carrier traveling toward the rinse jet when positioned at either of opposite ends of the machine.

21. In a washing machine, means to advance carriers of articles through the machine in a succession of intermittent movements, and means 40 for directing sprays of liquid against the carriers of articles as they are moved through the machine comprising a spray header having a plurality of pipes spaced transversely thereof, said pipes extending in a generally longitudinal direction of the machine but somewhat inclined transversely thereto, each pipe extending longitudinally for a distance greater than the extent of a plurality of advancing movements of a carrier by said advancing means, a plurality of longitudinally spaced spray jets carried by each pipe, the positioning and inclination of the several pipes providing liquid sprays from the spray jets which are staggered transversely of the machine so as to effectively cover the lateral extent of a carrier, the spray jets of each pipe having a spacing coordinated with the amplitude of said intermittent movements to provide sprays spaced apart in the direction of carrier movement and having a spacing where they are effective on the carriers 50 which spacing is different from the extent of an advancing movement of the carrier and from multiples thereof so that the sprays issuing from said jets impinge upon each carrier at a plurality of different areas during the several rest intervals 55 when said carrier is stationary and within range of the sprays of said header.

22. In a washing machine of the character described, means to advance carriers of articles through the machine in a succession of intermittent movements, means for directing sprays of liquid against the carriers of articles as they are moved through the machine comprising a spray system having a series of nozzles spaced transversely of the machine, said series of nozzles extending in a generally longitudinal direction of

the machine but arranged to direct spray jets transversely with respect to the line of advance of said carriers, said series of nozzles extending longitudinally for a distance greater than the extent of a plurality of advancing movements 5 of a carrier by said advancing means, the positioning of the several jets providing liquid sprays which effectively cover the lateral extent of a carrier, the spray jets having a predetermined definite spacing coordinated with the amplitude 10 of said intermittent movements to provide sprays spaced apart in the direction of carrier movement and having a spacing where they are effective on the carriers which spacing is different from the extent of an advancing movement of 15 the carrier and from multiples thereof, so that the sprays issuing from said jets impinge upon the carrier and the articles thereon at different areas during each of the several rest intervals when said carrier is stationary and within range 20 of the sprays of said header, the summation of the several areas thus impinged upon by the several sprays being such that there is uniform distribution of the sprayed liquid throughout the entire article carrying horizontal extent of the 25 carrier both during the several periods of its non-advance and also during the period of passage of the carrier through the spray zone, whereby to utilize effectively and economically the sprayed 30 liquid.

23. In a washing machine adapted to receive carriers of articles to be washed during transit through the machine; means for supporting the carriers during transit, means for advancing the carriers through the machine, said supporting 35 means including a suspension frame, means for imparting an oscillatory movement to said suspension frame, said carrier advancing means comprising members adapted to engage the carriers during movement of the oscillatory suspension frame in one direction and additional members adapted to engage the carriers during movement of the suspension frame in the opposite direction.

24. In a washing machine adapted to receive carriers of articles to be washed during transit through the machine; means for supporting the carriers during transit, means for imparting oscillatory movement to said supporting means, means on the supporting means to positively provide 40 movement of the carriers with the supporting means upon movement of the supporting means in one direction, and means to move the carriers relatively to the supporting means upon movement of the supporting means in the opposite 45 direction.

25. In a washing machine having a washing station, an oscillatory frame, means for imparting an oscillatory movement to said frame, means associated with said frame and spaced longitudinally thereof for positively advancing articles in a series of intermittent movements during oscillation of said frame, said advancing means being effective on both sides of the washing station and ineffective at the washing station whereby advancing movement of the articles is stopped to provide a dwell at the washing station during continued oscillation of said frame.

26. In a washing machine having a washing station and a rinsing station, an oscillatory frame, 70 means for imparting an oscillatory movement to said frame, means associated with said frame adjacent the inlet end of the machine for positively advancing a rack of articles in a series of intermittent movements into the washing station 75

tion during oscillation of said frame, and additional advancing means associated with said frame adjacent the outlet end of said machine for positively advancing a rack of articles through 5 the said rinsing station, said advancing means adjacent the inlet end being operatively spaced from said advancing means adjacent the outlet end to stop advancing movement so that a rack remains in said washing station during continued oscillation of said frame until a succeeding 10 rack is advanced into the washing station by said advancing means adjacent the inlet end and pushes the preceding rack out of the washing station, said additional advancing means adjacent the outlet end then picking up said preceding rack and positively advancing it in a series of intermittent movements through said rinsing station during continued oscillation of said frame and while the succeeding rack dwells in 15 the washing station.

27. In a washing machine having a washing station with wash liquid sprays and a rinsing station with rinse liquid sprays, an oscillatory frame, means for imparting an oscillatory movement to said frame, means associated with said frame adjacent the inlet end of the machine for positively advancing racks of articles in a series of intermittent movements as far as said washing station during oscillation of said frame, 25 means for continuously supplying wash liquid to said wash liquid sprays during oscillation of said frame, and additional advancing means associated with said frame adjacent the outlet end of said machine for positively advancing a rack 30 of articles through the said rinsing station, said advancing means adjacent the inlet end being operatively spaced from said advancing means adjacent the outlet end to stop advancing movement of a rack to provide a dwell at the washing 35 station during continued oscillation of said frame until a succeeding rack is moved into the washing station by said advancing means adjacent the inlet end and pushes the preceding rack out of the washing station, said additional advancing means adjacent the outlet end then picking up the rack when pushed out of the washing station and positively advancing it by a series of intermittent movements through the rinsing station, and means responsive to the passage of the 40 rack through the rinsing station for automatically supplying rinse liquid to said rinse liquid sprays and for automatically terminating the said supply of rinse liquid as the rack is advanced beyond the said rinsing station.

55. 28. In a washing machine, the combination with a rack carrying a plurality of feed members spaced longitudinally of the rack, of means for supporting the rack, and means for advancing the rack relative to the supporting means in a series of intermittent movements, each of which movements is of substantially less extent than the longitudinal length of a rack, one of said means comprising an oscillatory suspension frame, flexible straps connected at the lower ends 60 to said frame and at the upper ends to a stationary part of the machine to freely suspend the frame, means for imparting an oscillatory movement to said frame of the amplitude required for a rack advancing movement of the order stated, said oscillatory movement being afforded by flexure of said straps suspending the said frame, said rack advancing means including dogs for engaging the feed members of said rack to 65 advance the rack relative to the supporting means 70

during the oscillatory movement of said frame in one direction.

29. In a washing machine having a stationary frame work, the combination with a rack having a plurality of feed members spaced longitudinally of the rack, of an oscillatory frame for supporting the rack, means for imparting an oscillatory movement to said frame of an amplitude which is substantially less than the longitudinal extent of said racks and which is coordinated to the spacing of the feed members, and means mounted on the machine framework and spaced longitudinally of the machine for engaging said rack feed members to advance the rack relative to its oscillatory supporting frame during movement of the frame in one direction for movement of the rack through the machine by a plurality of intermittent movements of comparatively small amplitude.

30. In a dishwashing machine of the character described adapted to receive racks of dishes to be washed, an oscillatory frame, means establishing driving connection between said frame and said racks during oscillation of said frame in one direction, means for imparting an oscillatory movement to said frame including reciprocatory driving means and resilient yieldable means connected to the driving means and the oscillatory frame to transmit movement therebetween, said resilient yieldable means comprising two parts and resilient means intermediate said parts for joining said parts to each other in yieldable relation one with respect to the other while maintaining said joined connection when said frame encounters a predetermined resistance to movement to thereby terminate rack advancing movement of said frame at any position within the range of oscillation thereof and while maintaining continued operation of said driving mechanism, said yielding connection between the said two parts then providing for continued oscillation of said frame throughout that portion of its normal range of oscillation behind the point where the said predetermined resistance is encountered to thereby intermittently relieve the racks from the application of forward feeding force during the continued operation of said driving mechanism thus providing for ready removal of the racks during such intervals of relief.

31. In a dishwashing machine of the character described adapted to receive racks of dishes to be washed, an oscillatory frame, means establishing driving connection between said frame and said racks during oscillation of said frame in one direction, means for imparting an oscillatory movement to said frame including a reciprocatory driving means and motion transmitting means between the driving means and the frame comprising a pair of members engaging one another and connected one to the driving means and the other to the frame, resilient means connected to said members for holding said members tensioned in predetermined definite positioning with respect to each other to afford a normal unyielding relationship for driven loads below a predetermined value and a yielding relationship under tension of the resilient means for loads exceeding the predetermined value, said resilient means effecting restoration of said predetermined positioning of said members upon termination of the excessive load and upon the non-driving stroke of said frame, the pressure on the racks being periodically released upon the non-driving stroke of said frame providing for ready withdrawal thereof.

32. In a washing machine adapted to receive

article carriers for transit therethrough, feeding means repeatedly effective to advance the carriers in a succession of intermittent steps, reciprocal driving means, motion transmitting means comprising a pair of members having pivotal interfit at spaced points and adapted to rock with respect to each other on either of the pivot points, said members being connected with the feeding means and driving means respectively, resilient means connecting the said members under tension, the points of attachment of the re-

silient means extending in a line perpendicular to a line through the said pivot points and substantially midway therebetween, said resilient means affording a normal unyielding relationship for driven loads below a predetermined value and a yielding relationship of substantially the tension of said resilient means throughout the range of yielding movement for loads above the predetermined value. 5
